DESIGN FOR A WELDING HELMET

Thomas M. Le Vasseur, Wyoming, Minn.

Application October 7, 1944, Serial No. 115,672

Term of patent 14 years

(Cl. D57—1)

To all whom it may concern:

Be it known that I, Thomas M. Le Vasseur, a citizen of the United States, residing at Wyoming, in the county of Chisago and State of Minnesota, have invented a new, original, and ornamental Design for Welding Helmet, of which the following is a specification, reference being had to the accompanying drawing, forming a part thereof.

In the drawing:

Fig. 1 is a side elevational view of a welding

helmet, showing the essential features of my design in full lines;

Fig. 2 is a fragmentary top plan view;

Fig. 3 is a front elevational view of the lens holder only; and

Fig. 4 is a rear elevational view thereof.

I claim:

The ornamental design for a welding helmet, as shown and described.

THOMAS M. LE VASSEUR.
